UNITED STATES PATENT OFFICE.

MANOEL V. WANDERLEY, OF NEW YORK, N. Y.

FIRE ESCAPE.

Application filed January 23, 1923. Serial No. 614,410.

To all whom it may concern:

Be it known that I, MANOEL V. WANDERLEY, a citizen of Brazil, residing at New York city, borough of Manhattan, in the county of New York and State of New York, have invented certain new and useful Improvements in Fire Escapes, of which the following is a specification.

This invention relates to fire escapes and 10 has particular reference to that type of safety apparatus known as a reel fire escape.

Among the objects of the invention is to provide a safety appliance of the nature set forth so designed as to be built or 15 attached to the wall on the inside of a building or room, adjacent to any convenient outside window, whence a person may at the time of a fire or other emergency pass quickly and safely to the ground or other 20 available landing.

Another object of the invention is to provide a safety apparatus of the nature stated including a rigid support projecting outward from the building wall and from or 25 through which a flexible connection for the person is designed to pass and be so guided as to insure that the person will pass downward safely cleared from the wall or any usual projections therefrom such as window 30 sills or the like.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a diagrammatic side elevation, parts in section, of a preferred embodiment and arrangement of my improvement.

Fig. 2 is an open view of the casing showing the main parts of the reel and controlling mechanism in elevation.

Fig. 3 is a vertical transverse section on the line 3—3 of Fig. 2.

Referring now more specifically to the drawings, in the wall W, preferably close to a window w, is secured or built a support or arm 10 shown as of tubular construction and having its outer end bent downward within 50 which is a guide roller 12, while at the inner

end is another guide roller 13. This arm 10 is rigid and sufficiently strong for its intended purpose.

On the inside of the wall, built within a suitable cabinet or secured against one of the walls of the room or building is a casing 14 within which are secured the principal parts of my mechanism but from which is extended a flexible member such as a cable 15 which is guided over the rollers 13 and 12 and to which a belt or equivalent body attachment 16 is adapted to be connected as by means of a ring 17 and snap hook 18 connected to the end of the cable by means of a chain 19, which is capable of withstanding effect of the elements and always be ready for use. The hook 18 is normally held engaged in a fixed position such as indicated by the hook 20 on the outside of the wall within convenient reach of a person at the window. The belt, together with the simple directions for the use of the apparatus, will be kept normally hanging inside of the window close to the casing 14. At the time of danger the operator or person to escape through and from the window will simply pass the belt around his body under his arms in practically the form indicated in Fig. 2 and then snap the ring 17 upon the hook 18 and leap from the window.

Within the casing is built or fastened a suitable strong rigid frame including a plate or bar 21 extending horizontally along the central portion of the back wall of the casing and whence it may be extended forward to any desired distance around the inside of the casing as indicated at 22 and constituting an inside frame. Journaled in the frame is a main shaft 23 upon which is fixed a reel 24 upon which the cable 15 is secured at its inner end and suitably coiled in normal position and from which the cable may pay out freely as the person descends from the window, subject to such control as is referred to below. The inner end of the shaft 23 is journaled in a member 25 constituting a portion of the frame. This frame lies in a plane approximately midway between the top and bottom of the casing and mainly at one side of the center thereof. On the end of the shaft outside the frame is fixed a toothed pinion 26.

The shaft 23 is sufficiently longer than the axial diameter of the reel to accommodate between the reel and the frame member 25

a sleeve 27, loosely journaled upon the shaft and comprising two integral members, a ratchet wheel 28 and a worm gear 29, the ratchet wheel being close adjacent to the 5 side of the reel.

Co-operating with the teeth of the ratchet wheel are one or more pawls 30 pivoted at 31 to the side of the reel and each urged by a leaf spring 32 toward the ratchet wheel, 10 said spring reacting against a stud 33. The pawls, when more than one are used, are preferably staggered with relation between their points and the teeth of the ratchet wheel so that one of the pawls will always 15 be sure to engage quickly with one of the teeth when the cable is unwinding from the reel, causing the reel to rotate in a counter clockwise direction as indicated by the arrow at the top of Fig. 2.

20 As a convenient means for automatically and quickly restoring the cable upon the reel when released from the person who has just used the apparatus, I associate with the reel one or more springs shown as in the 25 form of coils and four in number. Two of the springs 34 are fastened at their inner ends upon a shaft 35 and at their outer ends upon an anchorage 36, both of which members are secured in a vertical portion or extension 37 of the internal frame work and comprising two parallel bars wholly at the side of the aforesaid inside frame. While I show two of these springs arranged side by side, and spaced by a suitable guard or 30 spacer 38 I wish it to be understood that any number or size of such springs may be used according to the strength or length required in each individual installation. In this connection it is to be noted that the 35 same apparatus is adaptable for use in connection with buildings of any usual height, the only variation being in the length of the cable 15 and the length or strength of the springs. Fixed in any convenient manner to the shaft 35 is a toothed gear 39 meshing with the pinion 26. With the rotation of the reel in the direction indicated in Fig. 2, the shaft 35 will be rotated in a clockwise direction, causing the springs 34 40 to be wound up. For additional strength of the springs I show another pair of springs 34' secured at their inner ends to a shaft 35' above the aforesaid springs and shafts and whose outer ends are anchored to an anchorage 36'. The shaft 35' is attached to a spur gear 39' of the same size as and meshing with the gear 39. The arrangement and operation of the springs 34' are the same as the parts earlier described except that the gear 39' rotates in the opposite direction from the gear 39 and consequently the springs are coiled in the opposite direction, as shown. By the time the person has reached the ground or landing 45 place sufficient additional power is stored in

the springs to return promptly the cable to the reel and the chain and belt to a position within easy reach at the window for use by another person in the manner above described. Sufficient power always remains in 70 the springs to keep the cable drawn well into the casing and tubular support 10 as shown in Fig. 1. The chain or a ring connecting the chain to the cable will prevent the chain from being drawn into the support 10 so that it will always be in reach of a person at the window either for use or other disposition in idle position as described.

75 The means for controlling the speed of rotation of the reel and hence the rate of descent of the person comprises a speed governor including a stationary clutch member 40 fixed at 41 to a stationary part of the mechanism and with which cooperates a clutch cone or plate 42 slidable upon but held from rotation in connection with a shaft 43 upon which is formed or secured a worm 44. 45 indicates a centrifugal weight member, somewhat like a fly wheel, but having a normally oblique position with respect to the axis of the shaft 43 upon which the weighted member is pivoted by a pivot pin 46 transverse to the axis of the shaft. On the side of the weighted member adjacent to the clutch sleeve is a cam 47 bearing against said sleeve. With the speeding up of the shaft 43 the weighted member tends to approach the dotted line position of Fig. 2, causing the cam 47 to crowd the clutch cone toward or into the clutch member 40, the degree of friction and therefore the rate at which the cone member may turn with respect to the clutch member being in direct proportion to the speed of the apparatus.

80 The worm 44 meshes with and is driven from a worm wheel 48 mounted on the end of the shaft 49 upon which or to which is secured a worm 50 having constant mesh with the worm gear 29 above described. It 85 will of course be understood that the number of threads or the pitch of the threads of the worms 44 and 50 and the corresponding pitch of the worm gears 48 and 29, will be determined according to speed to be provided for in each installation. When the cable pays out from the reel, causing the 90 reel to rotate to the left as shown, the worm gear 29 will be rotated in the same direction, being fixed to the same shaft 23. This 95 will cause rotation of the shaft 49 as indicated by the arrow thereon in Fig. 2, and thus the weighted member 45 will be rotated at 100 relatively high speed and always in the same direction. When the springs act to 105 wind up automatically the cable upon the reel again, the pawls will ride idly over the ratchet teeth 28 while the governor mechanism will be idle. Thus it will be seen and 110 as borne out by extensive experience with 115

the apparatus, a person may escape quickly and safely from a burning building or other occasion of danger by simply attaching the belt as stated and leaping from the window 5 and when he reaches the landing place the belt on detachment from his person will be returned to the window for subsequent use. Furthermore, it will be noted that no manual governing means are provided or necessary, 10 a feature of tremendous importance considering that in the majority of cases, the persons to escape from such premises are women, children, or other persons more or less physically incapable, by reason of 15 age or temporary infirmity, to have either strength or presence of mind sufficient to manipulate manual controlling means such as have been proposed heretofore in connection with reel fire escapes. This apparatus 20 has proved to be thoroughly safe and efficient as well as rapid in its action.

I claim:

1. In a fire escape, the combination of a casing having means for securing it within 25 a building, a rectangular frame within the casing intermediate of its top and bottom, means to secure rigidly one side of the frame against the adjacent side of the casing while the opposite side of the frame extends approximately along the center of the casing, a 30 shaft journaled in the frame and projecting through and beyond the latter mentioned

side thereof, a power member fixed to the projected end of the shaft, a reel fixed to the shaft within the frame, a sleeve journaled 35 upon the shaft between the reel and said latter mentioned side of the frame, said sleeve carrying a ratchet wheel and a gear wheel, a cable wound upon the reel, a pawl carried by the reel and co-operating with 40 the ratchet wheel to cause rotation of the sleeve when the cable unwinds from the reel, automatic means operated by said gear wheel to regulate the speed at which the cable may unwind from the reel, and power 45 means located in the space between the frame and the remote side of the casing for quickly rewinding the cable upon the reel, said power member serving to store power in the power means while the cable is unwinding. 50

2. A fire escape as set forth in claim 1 in which a vertical frame extension is located in the space between the rectangular frame and the remote side of the casing and the 55 power means comprises a pair of parallel shafts journaled in said vertical frame extension, gears between said shafts to cause simultaneous rotation thereof, and a plurality of coil springs within the frame extension and having their ends attached to said shafts. 60

In testimony whereof I affix my signature.
MANOEL V. WANDERLEY.
